(57) **CLAIM**

The design for a maraca, as shown and described.

DESCRIPTION

FIG. 1 is a side elevation view of a maraca showing my new design, the opposite side being identical;

FIG. 2 is a front elevation view thereof, the rear view being identical;

FIG. 3 is a top view thereof;

FIG. 4 is a bottom view thereof; and,

FIG. 5 is a perspective view thereof.

The other side view is the same as FIG. 1. The rear view is the same as the front view.
